UNITED STATES PATENT OFFICE.

WALTER O. SNELLING AND WILLIAM R. LAMS, OF ALLENTOWN, PENNSYLVANIA,
ASSIGNORS, BY MESNE ASSIGNMENTS, TO TROJAN POWDER COMPANY, OF NEW
YORK, N. Y., A CORPORATION OF NEW YORK.

NITROSTARCH EXPLOSIVE AND METHOD OF MANUFACTURING SAME.

1,329,211.

Specification of Letters Patent. Patented Jan. 27, 1920.

No Drawing.

Application filed June 22, 1918. Serial No. 241,354.

To all whom it may concern:

Be it known that we, WALTER O. SNELLING and WILLIAM R. LAMS, citizens of the United States, and residents of Allentown, 5 Lehigh county, Pennsylvania, have invented certain Improvements in Nitrostarch Explosives and Methods of Manufacturing Same, of which the following is a specification.

10 Our invention relates to organic nitrate explosives and more particularly to nitro-starch explosives and their manufacture.

The problem of stabilizing nitro-starch in the preparation of nitro-starch explosives 15 presents difficulties, by reason of the fact that certain organic bodies well recognized as among the best stabilizing agents for other nitro-explosives, have not been usable with nitro-starch without injurious effect 20 upon the explosive. Nitro-starch is very readily colloided by a large number of organic substances, and such colloidization, even when it is only superficial and does not extend materially into the substance of the 25 nitro-starch granules, acts injuriously upon the nitro-starch. The stability of nitro-starch which is partly colloided is usually much less than is the corresponding stability of the uncolloided nitro-starch, and

30 the sensitiveness to detonation is also influenced, colloided nitro-starch being much more difficult to detonate than uncolloided nitro-starch, thus making the use of a very strong detonator necessary, where any considerable amount of colloidization has occurred.

There are certain substances, such as 35 rosanilin base, and diphenylamin, which are well recognized as stabilizing agents in connection with nitro-cellulose products. Owing to the greater ease with which nitro-starch tends to colloid, the introduction of these materials into the manufacture of nitro-starch explosives has been limited, and 45 accordingly the use of these valuable stabilizing agents has in a measure been prevented.

We have discovered that the presence of 50 a heavy mineral oil, such as a medium or heavy lubricating oil, tends to wholly prevent the colloidizing action of basic stabilizing agents, without lessening in any way their stabilizing properties. We find that

a heavy lubricating oil will dissolve from ten to thirty per cent. of its weight of 55 diphenylamin for example (the solvent action being greatly facilitated by warming the oil somewhat), and that this mixture of oil and diphenylamin has stabilizing, but not colloidizing, properties. It appears that 60 the oil acts as a protection against colloidization of the nitro-starch, the oil probably covering the surface of the nitro-starch granules with a thin film, and this film of oil-saturated nitro-starch resisting the col- 65 loidizing action of the stabilizing agent.

In the practice of our invention, we use only small amounts of oil, and very small amounts of the stabilizing agent. For example, with a finished explosive containing 70 25% of nitro-starch, and a total of about 70% of sodium and ammonium nitrates, we may use from one-half of one per cent. to a total of about 2% of oil, and this oil contains from 20% to 50% of its weight of the 75 stabilizing agent, thus making the total amount of stabilizing agent in the explosive vary from about one-tenth to three-tenths per cent.

As an illustration of a nitro-starch powder 80 made up according to the present invention, we give the following formula:—

Nitrated starch	25.0%	
Ammonium nitrate	33.0%	85
Sodium nitrate	38.2%	
Charcoal	2.0%	
Sodium bicarbonate	.5%	
Oil	1.0%	
Diphenylamin	.3%	90
		100.0%

In making such an explosive, the oil is preferably warmed to about 80° C., and the proper amount of diphenylamin is dissolved 95 in it. This treated oil is then preferably added to the mixture of sodium and ammonium nitrates, and this mixture is rolled or stirred until all of the grains of the sodium and ammonium nitrate have been 100 thoroughly coated with a thin film of the treated oil. Preferably the sodium and ammonium nitrates are quite warm before this mixing takes place, so as to prevent too quick a chilling of the treated oil, which 105 would precipitate some of the dissolved di-

phenylamin. The other ingredients of the powder are then mixed with the oil treated nitrates in any suitable manner. If desired the nitrated starch may also be preliminarily 5 treated with the solution of stabilizing agent in oil.

By dissolving the stabilizing agent in oil, we obtain the further advantage of its uniform distribution. Most sodium nitrate 10 contains small amounts of iodids and iodates, and these two substances, by mutual reaction, set free minute amounts of iodin, which when the sodium nitrate is mixed with nitro-starch, have a pronounced de- 15 stabilizing action on the nitro-starch. Diphenylamin has the ability of taking up these minute amounts of iodin, thus protecting the nitro-starch from their action, but if the diphenylamin were to be added as 20 a powder, for example, it is evident that a very large amount would be required, in order to insure that sufficient was present on and about each grain of the nitrate, to prevent the iodin from that grain reaching 25 an adjacent nitro-starch granule and injuring it. By dissolving diphenylamin in oil, and then stirring the sodium and ammonium nitrate grains with a minute amount of this treated oil, each particle of the nitrate be- 30 comes coated with a film of the diphenyl- amin-containing oil, and accordingly any traces of iodin set free by reaction within that grain is caught on the surface of the grain by the diphenylamin there present, 35 and is prevented from reaching the nitro- starch granules, although these also have a minute film of the diphenylamin-containing oil on them, thus giving a second point at which any traces of iodin may be caught.

40 While we prefer, in carrying out our invention, to dissolve the stabilizing agent in oil before incorporating said agent with other ingredients, other methods of manufacture may be employed. For example, di- 45 phenylamin free from oil, can be added to the heated sodium nitrate, or to the mixture of sodium and ammonium nitrates, and the heated mixture rolled or tumbled for some time at a temperature of preferably about 50 50° C. or higher. Nitro-starch, previously mixed with a sufficient quantity of a heavy mineral oil to coat the nitro-starch particles with a thin film of said oil, is then thor- 55oughly mixed with the treated inorganic nitrate, and the oil serves its function of protecting the nitro-starch grains from the colloidizing effect of the diphenylamin.

60 By referring in our specification to diphe- nylamin as a suitable stabilizing agent for the practice of our invention, we do not, in its broader aspects, wish to be limited to that particular agent, as other stabilizing agents having colloidizing properties may be successfully employed with nitro-starch by 65 the method above outlined—such for ex-

ample as other organic bodies containing an amino group. The colloidizing action is prevented by the presence of mineral oil.

As to the mineral oil, we have obtained 70 satisfactory results with medium or heavy lubricating oil, but do not wish to be limited to this as other suitable heavy mineral oils may readily be substituted and are available on the open market.

75 We claim:

1. The method of treating nitro-starch with a stabilizing agent which consists in dissolving said agent in oil and thoroughly mixing therewith the nitro-starch to disseminate the stabilizing agent uniformly 80 among the nitro-starch particles.

2. The method of treating nitro-starch which consists in thoroughly mixing the same with an organic colloidizing agent in the presence of mineral oil in sufficient quantity 85 to provide the nitro-starch particles with a coating of said oil and thereby prevent colloidizing of the nitro-starch by the organic body.

3. The method of treating nitro-starch 90 which consists in thoroughly mixing the same with an organic stabilizing agent in the presence of a heavy mineral oil in sufficient quantity to substantially wholly dissolve said organic agent.

4. The method of treating nitro-starch which consists in acting thereon with an organic body in the presence of an oil solvent thereof, thereby stabilizing the nitro-starch and preventing colloidization of the nitro- 95 starch by the organic body.

5. The method of treating nitro-starch which consists in acting thereon in the presence of mineral oil with an organic body containing an amino group.

6. The method of stabilizing nitro-starch which consists in acting thereon with di- 100 phenylamin in the presence of a heavy mineral oil.

7. The method of manufacturing nitro- 110 starch explosives containing an inorganic nitrate which consists in thoroughly mixing said nitrate with a minute quantity of a mineral oil solution of an organic body possessing the property of stabilizing nitro-starch, and then incorporating with the oil-treated nitrate the nitro-starch and other ingredients 115 of the explosive mixture.

8. The method of manufacturing nitro- 120 starch explosives containing an inorganic nitrate which consists in thoroughly mixing said nitrate with a minute quantity of a mineral oil solution of an organic body containing an amino group, and then incorporating with the oil-treated nitrate the nitro-starch and other ingredients of the explosive mixture.

9. The method of manufacturing nitro- 125 starch explosives containing an inorganic nitrate which consists in mixing said nitrate 130

- with diphenylamin dissolved in a heavy mineral oil, and then incorporating with the treated nitrate the nitro-starch and other ingredients.
- 5 10. The method of manufacturing nitro-starch explosives containing an inorganic nitrate which consists in mixing said nitrate with a minute quantity of a mineral oil solution of an organic body possessing the property of stabilizing nitro-starch and then incorporating therewith nitro-starch thoroughly mixed with a minute quantity of mineral oil.
- 10 11. The method of manufacturing nitro-starch explosives containing an inorganic nitrate which consists in dissolving diphenylamin in a heavy mineral oil at a temperature of about 80° C., thoroughly mixing with the inorganic nitrate a sufficient quantity of said solution to thoroughly coat the particles of said nitrate with a thin film of said oil, and then incorporating with the oil-treated nitrate the nitro-starch and other ingredients of the explosive mixture.
- 25 12. A nitro-starch explosive containing an organic stabilizing agent and a mineral oil.
13. A nitro-starch explosive containing diphenylamin and a mineral oil.

14. A nitro-starch explosive containing diphenylamin and a mineral oil, the diphenylamin constituting from about one-tenth to about three-tenths per cent. by weight of the entire explosive mixture.

15. A nitro-starch explosive containing a mineral oil solution of diphenylamin, the oil comprising about one-half of one per cent. to about two per cent. by weight of the entire explosive, and the diphenylamin comprising from about one-tenth to three-tenths per cent. by weight of the entire explosive.

16. An explosive containing nitro-starch, approximately 25%; ammonium and sodium nitrates, approximately 70%; diphenylamin approximately .1% to .3%; and mineral oil approximately .5% to 2%.

17. An explosive mixture comprising nitro-starch approximately 25%; ammonium nitrate approximately 33%; sodium nitrate, approximately 38%; charcoal, approximately 2%; sodium bicarbonate, approximately .5%; diphenylamin, approximately 3%; mineral oil, approximately 1%.

WALTER O. SNELLING.
